UNITED STATES PATENT OFFICE.

ERIK STEENBERG, OF HELLERUP, DENMARK.

COMBINED CHURNING AND EMULSIFYING MACHINE.

Application filed August 14, 1922. Serial No. 581,893.

To all whom it may concern:

Be it known that I, ERIK STEENBERG, manufacturer, No. 33, Jornsborvej, Hellerup, county of Copenhagen, Denmark, have 5 invented certain new and useful Improvements in Combined Churning and Emulsifying Machines, of which the following is a specification.

The present invention relates to a machine 10 rendering it practicable, at a certain temperature, pressure and counter-pressure, to churn and emulsify most intensively any liquid substance. It may be stated that a combined churning and emulsifying machine 15 of this kind will be useful mainly in the manufacture of margarine, but also for other industrial purposes.

The invention is shown on the drawing, Fig. 1 showing, in vertical longitudinal 20 section, a horizontally disposed construction of the machine,

Fig. 2, on a larger scale, a section along the line II—II in Fig. 1,

Fig. 3 a tightening device adapted to be 25 used in the machine,

Fig. 4 an obliquely disposed construction of the machine, and

Fig. 5 a vertically disposed construction. 30 *a* indicates a cylindrical vessel in which the churning and emulsifying operation is performed. In order that the substance contained in the vessel *a* may constantly be maintained at the temperature necessary for the favourable performance of the process 35 the cylinder *a* is encircled by a jacket *b* with the necessary usual supply and discharge pipes not shown on the drawing, in such a manner that there is provided a steam or water jacket outside of the vessel. 40 The vessel *a* is fitted with a supply hopper *c* and a discharge tube *d* with regulating valve *e*.

In the end bottoms of the vessel bearings 45 are provided for a shaft *f*, which is rotated in the direction of the arrow *k* by means of suitable members. On this shaft there is provided a conveyor worm *g* fitting quite closely against the inside of the cylinder and being provided with numerous small holes 50 in the spirals or threads thereof as shown on the drawing. The worm extends throughout the length and occupies the entire interior space of the cylinder.

The worm *g*, on the portion of the same 55 directly opposite the supply opening *c* and

serving solely to transport the mass, is tight or has only a few holes, while the remaining portion, as mentioned above is fitted with holes *h* the shape, size and number of which are determined by the substance to be 60 churned or emulsified and by the pressure desired to be maintained in the vessel.

When the shaft *f* is rotated in the direction indicated by the arrow *k* in Fig. 1, the material which is filled into the hopper *c* 65 will be conveyed by the worm into the closed portion of the tube, and when the pressure in the latter has become sufficiently high, the said material will be pressed back through the holes *h* in the worm *g*, and as 70 the worm is constantly rotated, the material will be in constant motion, partly in the interstices along the threads of the worm and partly through the holes *h*. Hereby a 75 very efficient emulsifying and churning effect will be attained and may, furthermore, be varied infinitely, the conditions depending merely on the rotary speed of the shaft, the pitch of the worm, the number and size of the holes and the diameter of the worm. 80

Fig. 3 shows a packing device for the worm. This packing is used when the interstice between the worm and the vessel *a* is so large that there will be danger of too much of the churned material being pressed 85 past the worm, and it consists of an L-shaped leather strip *i* attached to the edge of the worm, the other leg of the said strip sliding on the inside of the vessel *a*. Besides or instead of the above mentioned holes *h* notches 90 or incisions may be provided in the edge of the worm.

Fig. 4 shows an obliquely disposed machine by which the natural counter-pressure due to the liquid's own weight will be larger 95 than in the construction shown in Fig. 1. Fig. 5 shows a vertically disposed machine, in which the counter-pressure is still larger than in either of the above mentioned constructions. 100

The machine may work with intermittent as well as with continuous discharge, the valve *e* being first closed, and the machine is then started and filled, and works then until the churning and emulsifying operation is finished whereafter the valve *e* is 105 opened and the machine emptied. When the machine is emptied, the valve is closed and the machine filled again. If the machine is to work continuously, it is filled 110

while running, and the valve *e* is adjusted until the desired pressure in the vessel has been attained.

5 The discharge through this valve will then be continuous.

As shown on Fig. 1 a return pipe may be applied from discharge pipe *d* to the other end of the cylinder.

Patent claims:

- 10 1. Combined churning and emulsifying machine including a cylindrical vessel having an inlet and a relatively small discharge located at an end opposite the inlet, a rotatably mounted perforated conveyor worm arranged within and extending throughout the length of the vessel and having its outer edges arranged in close relation to the inner surface of the vessel and operating in such a manner that the material is pressed 15 towards the discharge end and is compacted at this end, and the worm in addition creating a high pressure to accelerate the emulsifying action, substantially as and for the purposes set forth.
- 20 25 2. Combined churning and smulsifying

machine including a closed cylindrical vessel, an inlet adjacent one end of the vessel, a relatively small valved control discharge pipe leading from the opposite end of the vessel, a conveyor worm rotatably mounted within the vessel and of a length equal to the length of the vessel, the spirals of the worm being perforated and the outer edges of the spirals of the worm being arranged in close relation with the inner surface of the vessel, the worm during rotation acting to press the material towards the discharge end of the vessel to compact the material at this end under a relatively high pressure and thereby accelerate the emulsifying action.

3. Combined churning and emulsifying machine as claimed in claim 2 wherein the return pipe extends from the discharge to the inlet end of the machine.
